UNITED STATES PATENT OFFICE.

JACOB B. ANDERSON, OF MERRILL, IOWA.

EXPANSION BURNISHING TOOL.

Application filed June 3, 1926. Serial No. 113,425.

My invention relates to a tool for sizing the inner diameters of wrist pin bearings, and the like, and it is my object to provide such a tool of simple, durable and inexpensive construction, in which the action upon the bushing of the bearing is produced by a burnishing process as opposed to cutting. 5

More particularly it is my object to provide a tool for use in working upon material 10 such as bronze or babbitt, the burnishing being done by bit or wedge having a rounded face adapted to contact with the material of the bearing.

A further object is to provide such a tool 15 having a removable bit of wedge-shape, actuated by an adjusting element, a novel connection being had between the adjusting element and the bit, whereby the bit may be retracted by a pin and slot connection, and 20 positive pressure be transmitted to the bit directly for expanding the same.

With these and other objects in view, my invention consists in the construction, arrangement and combination of the various 25 parts of my device, whereby the objects contemplated are attained, as hereinafter more fully set forth, pointed out in my claim and illustrated in the accompanying drawings, in which:

Fig. 1 is a plan view of the tool.

Fig. 2 is a sectional view illustrating the tool received in a bearing.

Fig. 3 is a transverse sectional view taken through the line 3-3 of Fig. 2.

Fig. 4 is a detail sectional view taken on the line 4-4 of Fig. 2.

I have discovered that by using a suitable rotatable burnishing tool a hard glazed finish can be given to a bushing such as bronze, 40 or babbitt, which has better wearing qualities than the finish produced by cutting. The metal in such an operation is compressed to give the bushing the proper size.

I have used the reference character 10 to 45 indicate the wrist pin bearing of a connecting rod, and the reference numeral 11 to indicate the bronze bushing therein.

The burnishing tool comprises a plug or shaft, 12, having a reduced portion, 13, and 50 an enlarged collar, 14, the latter to prevent the tool from dropping through the bushing when the tool is used in an upright position. A squared head, 15, is designed to receive a wrench for rotating the plug.

A slot, 16, is cut longitudinally in the plug and receives a wedge-shaped bit or burnish-

ing wedge, 17. The slot, 16, is cut upon the slant to correspond with that of the wedge, 17, so that the outer edge of the wedge will remain parallel to the axis of the plug. 60 This outer edge is finished upon a curve, as at 18 (see Fig. 3), the curve being of much less diameter than the bushing into which the tool is inserted.

The diameter of the plug, 12, is very little 65 less than that of the bushing, 11. I find that better results are thus obtained.

I provide a very simple means for moving the wedge longitudinally in the slot, 16, in order to adjust it radially of the plug, 12. 70 An opening, 19, is tapped into the end of the plug, and this opening is threaded, as at 20, during a portion of its length. A rod, 21, having a reduced shaft portion, 22, is slipped into the opening, 19, and thence extended rearwardly through the end of the plug. A threaded sleeve, 23, is then received over the reduced portion, 22, and the end of the reduced portion swaged down, as at 24. 75 The threaded sleeve, 23, has an axial head, 25, to receive a wrench for rotating the sleeve.

The pin, 26, on the rod, 21, prevents 80 removal of the rod from the tool, and serves to fit within a slot, 27, in the butt end of the wedge, 17.

A notch is cut in the end of the wedge, 17, below the slot, 27, to form a shoulder, 28, which is received against the end of the rod, 21. 85

When the rod is moved inwardly in the plug, the pressure from the end thereof is transmitted to the shoulder, 28, to force the wedge outwardly against the surface which it engages. When the rod is moved in the 90 other direction the wedge is retracted by means of the pin and slot connection.

A series of gauge marks, 29, are provided 95 on the reduced portion, 13, and the end of the wedge, 17, coacts therewith to indicate the amount of expansion.

The wedge is held in place by a set screw, 31, which coacts with a slot, 32, in the wedge, parallel to the lower edge thereof. The 100 wedge may be removed by removing the screw.

Some changes may be made in the construction and arrangement of the parts of my invention without departing from the real spirit and purpose of my invention, and 105 it is my intention to cover by my claim any modified forms of structure or use of me-

chanical equivalents which may be reasonably included within their scope.

I claim as my invention:

In a device of the class described, a cylindrical plug having a longitudinally inclined slot, an axial opening in the end of the plug communicating with said slot, said opening being threaded, a burnishing wedge slidably received in the slot, said wedge having a slot 10 and a shoulder at its butt end, a rod having a pin received in the slot of said wedge, and

its end engaging said shoulder, said rod being slidably mounted in the threaded opening and having a reduced portion, a threaded sleeve receiving said reduced portion and threaded into the threaded opening, means for transmitting rotating movement to said sleeve, and means for transmitting rotating movement to the plug. 15

Signed in the county of Plymouth and 20 State of Iowa, this 27th day of May, 1926.

JACOB B. ANDERSON.
